FIG. 5.

FIG. 6.

UNITED STATES PATENT OFFICE.

WILLIAM H. GETTZ, OF PHILADELPHIA, PENNSYLVANIA, AND EDWARD C. FOSTER, OF PITMAN, NEW JERSEY, ASSIGNEES OF ONE-THIRD TO WILLIAM E. ALLOWAY, OF PHILADELPHIA, PENNSYLVANIA.

BURGLAR-ALARM.

1,105,899.

Specification of Letters Patent.

Patented Aug. 4, 1914.

Application filed October 17, 1913. Serial No. 795,630.

To all whom it may concern:

Be it known that we, WILLIAM H. GETTZ and EDWARD C. FOSTER, citizens of the United States, residing, respectively, at 5 Philadelphia, county of Philadelphia, and State of Pennsylvania, and Pitman, county of Gloucester, and State of New Jersey, have invented certain new and useful Improvements in Burglar-Alarms, of which the following is a specification.

Our invention relates to improvements in burglar alarms, and more particularly to burglar alarms of the detonating type, the object of the invention being to provide 15 improved means operated when a window or door is opened to cause the operation of a plunger and the discharge of a blank cartridge.

A further object is to provide improvements of this character which are extremely 20 simple in construction, which do not disfigure a door or window, and which can be placed in operative position by any ordinary householder not requiring skilled labor for 25 the purpose.

With these and other objects in view, the invention consists in certain novel features of construction and combinations and arrangements of parts, as will be more fully 30 hereinafter described and pointed out in the claims.

In the accompanying drawings: Figure 1 is a fragmentary perspective view illustrating our improvements as applied to a window. Fig. 2 is a view in elevation of the device with the outer casing removed. Fig. 3 is a view in section on the line 3—3 of Fig. 2. Fig. 4 is a view in elevation illustrating our improvements as applied to a door. Fig. 5 is a view in elevation at right angles to Fig. 4. Fig. 6 is a view in elevation of the construction shown in Fig. 4 but omitting the removable outer casing. Fig. 7 is a view in section on the line 7—7 of Fig. 6. Fig. 8 is a view in transverse section on the line 8—8 of Fig. 6. Fig. 9 is a view in elevation illustrating the pivoted dog 31.

Referring to the construction illustrated in Figs. 1, 2, and 3, 1 represents a window frame and 2 an ordinary sliding window sash to which latter a base plate 3 is secured.

by screws 4. The base plate 3 at its upper and lower ends is provided with outwardly projecting flanges 5 and 6 respectively and at its lower end is formed with an integral 55 barrel 7 adapted to receive an ordinary blank cartridge 8 and hold the same in position to be engaged by the pointed end 9 of a plunger 10. The plunger 10 is mounted to slide in bearings 11 integral with base plate 60 3, and is provided between said bearings with a coiled spring 12, the upper end of which bears against the upper bearing 11, and the lower end bears against a cross pin 13 projected through an opening 14 in the 65 plunger, and one end of which is preferably longer than the other and is adapted to be manually manipulated to remove the plunger as will hereinafter appear. The shorter end of the pin 13 is adapted to be engaged 70 by a tripping lever 15 pivotally supported between its ends on a pin 16 secured in base 3, and said lever 15 is connected by a coiled spring 17 with the upper flange 5 so as to hold the lever in normal position. One end 75 of this lever 15 projects beyond the edge of the sash and is adapted when the sash is elevated to engage a block 18 fixed to the frame 1, so that the tripping lever will be caused to pivot and its inner end engaging 80 pin 13 will elevate the plunger 10 against the action of spring 12 until the lever 15 rides off the end of the pin, when the spring 12 will force the plunger downwardly and discharge the cartridge. A removable casing 19 is positioned over the base 3, and this casing is provided in one side with an opening 22 through which pin 13 projects, one wall of this opening 19 having notches 20 therein in which the pin 13 may be moved 90 to lock the plunger in an elevated position and out of the way of tripping lever 15. This is desirable when placing a new cartridge in the barrel 7, and is also desirable during the day when the alarm is not set. 95 An opening 21 is provided in the casing 19, so that a cartridge may be readily inserted or removed without removing the casing.

In the construction illustrated in Figs. 4 to 9 inclusive, we employ a base plate 3 100 which is secured by screws 4 to a door 23, and this base plate 3 has flanges 5 and 6,

barrel 7, and bearings 11, the same as in the form first described. In the bearings 11, the plunger 10 is mounted and pressed downwardly by the spring 12 to force the pointed end 9 into contact with the cartridge 8. A pin 13 projects through the plunger 10 and is adapted to be manipulated to manually operate the plunger. A bracket 25 is fixed to base 3 and is provided at its 5 upper end with a vertical pin 26 on which a horizontally swinging tripping lever 27 is pivotally supported between its ends. A spring 28 is secured at its lower end by a screw 29 to base 3 and exerts a pressure on one end of lever 27 to hold the latter in 10 normal position, and when the device is set, the plunger 10 will be moved upwardly and the pin 13 positioned over the upper surface of the inner end of lever 27. The inner 15 end of lever 27 is beveled at one side as shown at 30, so that the pin 13 may be readily elevated past the lever, forcing the latter outwardly until the pin reaches the proper height, when the spring 28 will move 20 the lever back under the pin. The outer end of the lever 27 engages a pivoted dog 31, the latter having a beveled upper end 32 over which the lever engages when the door moves to closed position, the dog pivoting 25 to allow such movement. A pin 33 acts as a stop to limit the pivotal movement of the dog in the opposite direction, so that when the door is opened, the dog 31 cannot pivot to allow the lever 27 to pass, hence the lever 30 35 40 45 is swung on the pivot 26 and pin 13 is released, allowing the plunger to be forced downwardly by the spring 11 and discharge the cartridge. The dog 31 is supported by a bracket 34 fixed to a block 35 on the door frame 36 and in proper position to be engaged by the lever 27. A removable casing 37, corresponding to casing 19, is connected to the base 3 and is provided with suitable openings and covers the working parts of the device.

It will be noted that in both forms of our invention, the opening of the door or window causes the operation of the plunger and the discharge of the cartridge, thus giving alarm to the householders as well as frightening the burglar.

Various slight changes might be made in the general form and arrangement of parts described without departing from our invention, and hence we do not limit ourselves to the precise details set forth, but consider ourselves at liberty to make such changes and alterations as fairly fall within the spirit and scope of the appended claims.

Having thus described our invention, what we claim as new and desire to secure by Letters Patent is:

1. A burglar alarm of the character described, comprising a base, a barrel integral with the base and adapted to support a

cartridge, bearings on the base in line with the barrel, and a plunger mounted in said bearings, of a pin projected through an opening in the plunger, a coiled spring around the plunger between one of the bearings and said pin, and a spring-held tripping lever for holding and controlling the release of the pin and the operation of the plunger, substantially as described. 70

2. A burglar alarm of the character described, comprising a base, a barrel integral with the base and adapted to support a cartridge, bearings on the base in line with the barrel, and a plunger mounted in said bearings, of a pin projected through an opening in the plunger, a coiled spring around the plunger between one of the bearings and said pin, a pivoted tripping lever on the base, a spring holding said tripping lever in normal position, and means engaged by the tripping lever to cause the release of the pin and the operation of the plunger, substantially as described. 75 80 85

3. A burglar alarm of the character described, comprising a base, a barrel integral with the base and adapted to support a cartridge, bearings on the base in line with the barrel, and a plunger mounted in said bearings, of a pin projected through an opening in the plunger, a coiled spring around the plunger between one of the bearings and said pin, a pivoted tripping lever on the base, a spring holding said tripping lever in normal position, means engaged by the tripping lever to cause the release of the pin and the operation of the plunger, said base having flanges at its upper and lower end, and a casing fitting over said flanges, substantially as described. 90 95 100

4. A burglar alarm comprising a base, a vertically disposed barrel on the base adapted to receive a cartridge, bearings on the base in line with the barrel, a spring-pressed plunger in said bearings, and a pin projecting through the plunger, of a horizontally swinging tripping lever over one end of which said pin is adapted to be positioned to support the plunger in an elevated position, and a pivoted dog adapted to be engaged by the tripping lever to swing the latter out of the path of the pin and permit the plunger to move downwardly and discharge the cartridge, substantially as described. 105 110 115

5. A burglar alarm comprising a base, a vertically disposed barrel on the base adapted to receive a cartridge, bearings on the base in line with the barrel, a spring-pressed plunger in said bearings, and a pin projecting through the plunger, of a horizontally swinging tripping lever over one end of which said pin is adapted to be positioned to support the plunger in an elevated position, a pivoted dog adapted to be engaged by the tripping lever to swing the latter out of 120 125 130

the path of the pin and permit the plunger to move downwardly and discharge the cartridge, said lever having a beveled inner end, and a spring secured to the base and engaging said inner end of the lever, holding the latter in normal position, substantially as described.

In testimony whereof, we have signed our

names to this specification in the presence of two subscribing witnesses.
